Inventor,
William J. Grotenhuis,

By Office, hole, Nut or screw. *Attest.*

UNITED STATES PATENT OFFICE.

WILLIAM J. GROTEHNHUIS, OF CHICAGO, ILLINOIS, ASSIGNOR, BY MESNE ASSIGNMENTS,
TO BIFLEX PRODUCTS COMPANY, OF WAUKEGAN, ILLINOIS, A CORPORATION OF
DELAWARE.

DESIGN FOR CLAMP FOR AUTOMOBILE BUMPER.

Application filed August 26, 1921. Serial No. 495,830. Term of patent 7 years.

To all whom it may concern:

Be it known that I, WILLIAM J. GROTEHNHUIS, a citizen of the United States, and residing in Chicago, in the county of Cook and State of Illinois, have invented a new, original, and ornamental Design for Clamp for Automobile Bumper, of which the following is a specification, reference being had to the accompanying drawing, forming a part thereof.

Figure 1 is a view in elevation of the

clamp as it appears from the front of the bumper, and

Figure 2 is a top plan view of the clamp.

I claim:

The ornamental design for clamp for automobile bumper, as shown.

WILLIAM J. GROTEHNHUIS.

Witnesses:

SARAH E. HARVEY,
LURLINE BULLWINKEL.
